CLAIM

The ornamental design for a dermatology report document, as shown and described.

DESCRIPTION

The sole FIGURE is a front view of a dermatology report document, showing our new design.

The peripheral broken lines represent an unclaimed boundary of the dermatology report document and form no part of the claimed design. Within the peripheral broken lines, the broken line showing of text and other features of the dermatology report document is for environmental purposes only and forms no part of the claimed design. The difference in crosshatch shading indicates a contrast of appearance and does not depict any particular color, texture, or material. The dermatology report document has no appreciable thickness.

1 Claim, 1 Drawing Sheet

TEST RESULTS

GENE EXPRESSION RISK	LINC00518:
STATUS:	PRAME:
MUTATION RISK STATUS:	TERT Promoter:

Expression of LINC00518 and/or PRAME is found in lesions with a histopathologic diagnosis of melanoma. If one or both of the genes are detected, the test is positive. High Risk driver mutations in the TERT promoter region are found in early cutaneous and metastatic melanoma. The presence of mutations in TERT gene promoter are associated with *in situ* and invasive melanoma.

Risk Status Interpretation:

- **LOW (GREEN):** Melanoma-associated gene expression and mutation risk status negative. Consider surveillance per standard of care.
- **MODERATE (ORANGE):** Positive for LINC00518 alone has a sensitivity of 84%. Positive for PRAME alone has a sensitivity of 83%. Recommend surgical biopsy consistent with AAD treatment guidelines for lesions clinically suggestive of cutaneous melanoma. Consider complete removal to full depth and breadth with clear margins.
- **HIGH (RED):** Positive for LINC00518 and PRAME combined have a sensitivity of 91%. Recommend surgical biopsy consistent with AAD treatment guidelines for lesions clinically suggestive of cutaneous melanoma. Consider complete removal to full depth and breadth with clear margins.
- ⊕ **Plus(⊕):** Positive for TERT alone has a sensitivity of 73%. TERT promoter mutations convey additional risk and probability of melanoma beyond LINC00518 or PRAME. Consider complete removal to full depth and breadth with clear margins.
